Des. 226,500
Patented Mar. 13, 1973

226,500

REFUSE RECEPTACLE OR THE LIKE

James D. Ezell, 108 Pineland Circle,
Raleigh, N.C. 27601

Filed Feb. 16, 1972, Ser. No. 227,009

Term of patent 14 years

Int. Cl. D7—06

U.S. Cl. D49—35

fig.1

fig. 2

fig. 3

fig. 4

fig. 5

fig. 6

fig.7

fig.8

fig.9

FIG. 1 is a perspective view of a refuse receptacle or the like showing my new design;

FIG. 2 is a front elevational view;

FIG. 3 is a right side elevational view, the left side being a mirror image thereof;

FIG. 4 is a rear elevational view;

FIG. 5 is a top plan view;

FIG. 6 is a bottom plan view;

FIG. 7 is a perspective view of a modified form of a refuse receptacle or the like showing my new design;

FIG. 8 is a side elevational view thereof; and

FIG. 9 is a rear elevational view thereof.

I claim:

The ornamental design for a refuse receptacle or the like, as shown and described.
